UNITED STATES PATENT OFFICE.

FRANK SEMPLE WILCOX, OF UNION, SOUTH CAROLINA.

MERCERIZING MACHINE.

Application filed February 6, 1926. Serial No. 86,489.

The present invention relates to improvements in mercerizing machines and has for an object to provide for a re-circulation of the wash water which flows over the skeins.

5 The invention is shown and described in connection with the well known Smith drum machine shown in U. S. Patent No. 983,543 granted February 7, 1911, in which perforated pipes are arranged above the skeins for 10 spraying water over the skeins after they have been raised out of the mercerizing bath. The wash water after passing over the skeins is at the present time wasted although its absorptive power is only partially used, only 15 a certain portion of the water coming in contact with the yarn. The water actually comes in contact with the yarn and is only partially saturated with the caustic solution. This water is also generally heated so that 20 by re-circulating the water until it reaches or approaches the saturation point, great economy is effected, not only in the saving of the water, but also in curtailing fuel expense.

25 According to the invention the wash water is re-circulated to the spray pipes above the yarn and is only permitted to waste slowly in comparison with former methods, only so much fresh water as is actually needed 30 being introduced into the closed circuit of the wash water.

With the foregoing and other objects in view, the invention will be more fully described hereinafter, and will be more particularly pointed out in the claims appended hereto.

In the drawings, wherein like symbols refer to like or corresponding parts throughout the several views—

40 Figure 1 is a diagrammatic view, showing parts in section of the Smith machine with the improved re-circulating arrangement applied thereto.

Figure 2 is a diagrammatic side view of 45 Figure 1, and

Figure 3 is a fragmentary plan view of the trough and connected pipe.

Referring more particularly to the drawings, 4 designates the tank for the mercerizing fluid in which the skeins carried by the 5 upper frame indicated by 5 are adapted to be immersed when the frame is lowered.

The skeins indicated at 6 in dotted lines in Figure 2 are wound about the upper and 55 lower pairs of rods or rollers 7 and 8 carried in the frame 5.

Above each skein is a perforated pipe 9 extending horizontally substantially the length of the skein and these pipes are, in the machine referred to, mounted in pairs at 60 opposite sides of the central part of the machine and connect with the headers 10 and 11 which supply the wash water thereto. The headers are connected at one end by the pipe 12. This pipe 12 is in turn coupled to 65 the supply pipe 13 having the controlling valve 14. The pipe 13 is in communication with a source of wash water usually steam heated or steam may be introduced into the pipe at any point in order to heat the in- 70 coming water.

After the wash water has been sprayed upon and flows over the skeins it is received upon the sloping plate 15 arranged above the tank 4, being deflected by this plate to 75 the opposite troughs 16 and 17. These troughs are usual parts of the Smith machine and they ordinarily carry the wash water directly to the sewer. According to the invention the ends of the troughs are 80 closed and pipes 18 and 19 connect with the troughs for the purpose of withdrawing the wash water therefrom. The pipes 18 and 19 are branch pipes which connect with the eduction pipe 20. A centrifugal or other 85 pump 21 is used to withdraw the water and to return it through the pipe 22 to the supply pipe 12. A steam pipe is indicated at 23 having the valve 24 for admitting steam into the system for the purpose of heating the 90 fresh wash water or for re-heating the re-circulated wash water.

In the use of the device the wash water is supplied to the headers 10 and 11 and is sprayed out through the perforated device 9 95 upon the yarn. This water flows through the yarn for the purpose of washing the mercerizing fluid therefrom and the water absorbs the caustic solution. After passing through or along the skeins the water drips 100 down upon the plate 15 and is directed to the troughs 16 and 17. From this point the wash water is withdrawn at a predetermined rate by the centrifugal pump 21 and passed back to the pipe 12 where it is returned to 105 the headers above. Fresh wash water is introduced through the pipe 13 from time to time, or continuously at a very slow rate through regulation of the valve 14 and steam may be admitted through the pipe 23 by 110 regulation of the valve 24 wherein necessary. In order to reduce the density of the

re-circulated water, openings 25 are made in the side walls of the troughs to permit overflow of the water to the sewer. The dotted line indicated at 26 indicates the water level 5 in the troughs and if additional wash water is introduced it will raise this level and cause an overflow at the openings 25 thus removing from the system some of the saturated, or nearly saturated wash water to make 10 room for the fresh supply coming in through the pipe 13.

In actual practice about one-half of the supply water is shown to be saved. This 15 is a substantial economy in the water itself and where steam is used to heat the water, a like substantial economy is effected in the use of the fuel.

It is obvious that various changes and modifications may be made in the details of 20 construction and design of the above specifically described embodiment of this invention without departing from the spirit thereof, such changes and modifications being restricted only by the scope of the following claims:

What is claimed is:—

1. In combination with a mercerizing machine having a tank, skein racks above the tank, spraying pipes above said racks and 30 troughs below the racks to receive wash water draining from the skeins, a pump connected to said troughs for withdrawing partially saturated wash water therefrom, a return pipe leading from the pump to said

spraying pipes for redelivering the wash 35 water thereto, means for supplying fresh wash water to said return pipe, and means for supplying steam to said return pipe for heating the fresh and recovered wash water.

2. In combination with a mercerizing machine having spraying headers, skein racks beneath the headers, and troughs for collecting the wash water dripping from the skeins, a fluid circuit including the troughs and said spraying headers for recovering 45 partially saturated wash water and redelivering the wash water to said spraying headers, means for adding fresh wash water to the circuit, means for heating the wash water in the circuit, and means for regulating the 50 removal of the saturated wash water accumulating in the troughs.

3. In combination with a mercerizing machine having a sprayer head, skein holders arranged beneath the head, and means for 55 collecting wash water dripping from the skeins, an eduction pipe connected to said wash water collecting means, a pump connected to said eduction pipe for drawing recovered and partially saturated wash 60 water from said means, a supply pipe leading from the pump to said sprayer head, a steam pipe connected to said supply pipe for heating the wash water passing therethrough, and a fresh water supply pipe connected to said sprayer head for replenishing the exhausted wash water.

FRANK SEMPLE WILCOX.
